CLAIM

The ornamental design for a control panel for a feed batching system, as shown and described.

DESCRIPTION

FIG. 1 is a front perspective view of a control panel for a feed batching system showing my new design;
FIG. 2 is a front elevational view thereof;
FIG. 3 is a side elevational view thereof;
FIG. 4 is an opposite side elevational view thereof;
FIG. 5 is a top plan view;
FIG. 6 is a bottom plan view thereof; and,
FIG. 7 is a rear elevational view thereof.
